PHOTOELECTRIC CELLS OF THE LAYER
TYPE AND METHOD OF PRODUCING THE
SAME

Ernst Presser, Berlin-Dahlem, Germany

Application April 2, 1937, Serial No. 134,685
In Germany April 8, 1936

3 Claims. (Cl. 136—89)

My invention relates to photoelectric cells of the layer type.

There are known photovoltaic cells of the above mentioned type comprising a base-plate, a layer of light-sensitive material such as selenium in crystalline form or another element of the sixth group of the periodic table of elements with or without materials of higher conductivity mixed thereto and a translucent homogeneous covering layer of conducting material in finely divided form upon and in intimate contact with the crystalline surface of said light-sensitive layer. Because of the extreme thinness of the covering layer it is rather difficult to connect wires or other conductors thereto for conducting an electric current to or from the cell, and this difficulty is even increased when the conductors are, as usual, simply pressed against said covering layer, since the even relatively feeble mechanical pressure injures the thin covering layer at the spot where it is applied so that the electric contact will be uncertain.

Therefore it has been proposed to provide such covering layers with conductive reinforcing ribs adapted to be connected to a conductor by soldering or by pressure. Preferably only the margin or a part of the margin of the covering layer is provided with such a reinforcing rib so as to have only the least possible reduction of the effective area of the cell. In certain cases it is even sufficient to provide only little spot-like reinforcements on the marginal portion of the covering layer. The reinforcing ribs or spots are usually applied to the cell by spraying metal upon the predetermined parts of it; the spraying can take place either before or after the application of the thin covering layer.

The photoelectric cells of the type referred to are usually protected by a layer of translucent varnish against injurious atmospheric influences. Since the varnishes which are best adapted for this purpose do not lend themselves well for spraying, the cells are varnished by immersing them into the varnish, and therefore the reinforcing ribs or spots are also covered by the varnish. However, since in most cases the electric connection of the cell to the conductors to be connected to it is effected by pressure contacts, the varnish layer covering the reinforcement ribs or spots causes difficulties by impairing the desired intimate contact between the contact pieces and the reinforcement ribs or spots.

According to my invention this drawback is eliminated by spraying upon these parts of the varnish layer which cover the said reinforcing

ribs, conducting material in such manner as to cause the varnish layer to be pierced by the sprayed material, thus rendering a conductive connection between the conducting layers under and upon the varnish layer. As the conducting layer sprayed upon the varnish layer does not need any protection against atmosphere influences, it gives the possibility of making a safe and effective electric contact between the thin translucent covering layer under the varnish layer and pressure contact pieces applied to the varnished surface of the cell.

Of course it is not necessary to spray conducting material upon all those parts of the varnish layer which cover reinforcing ribs of the translucent covering layer; in many cases it may suffice to apply sprayed conducting material only to a fraction of those parts of the varnish layer. For example, the reinforcing rib may have the form of a ring covering the marginal portion of the translucent covering layer while the conducting material piercing the varnish layer can be sprayed upon the same in the form of round spots distributed along the ring-shaped reinforcing rib.

My invention is illustrated in the accompanying drawing by way of example.

Fig. 1 is a cross section of a photoelectric cell according to the invention, and Fig. 2 is a plane view thereof.

A metallic base plate 1 carries a light-sensitive layer 2. The marginal portion of this layer is covered by a metallic ring-shaped reinforcing rib 3 which is applied to the layer 2 by spraying. This reinforcing rib 3 may be produced by placing a mask having a ring shaped opening over layer 2 and spraying metal into the ring-shaped opening until an amount of metal is deposited upon the exposed portion of layer 2 which is sufficient to produce the desired height of rib 3. A somewhat rounded section of the rib 3 will be produced if more particles are sprayed upon the central portion of the section of the rib than upon the outer portions of such section and such rounded section may be produced when employing a mask, for such mask will shade the side portions of the annular opening more than the central portion when the metal is being sprayed. The central portion of the layer 2 is covered by a thin translucent conducting covering layer 4 which is in conductive contact with the rib 3. The base-plate 1 is the one electrode and the covering layer 4 is the other electrode of the cell. The covering layer 4 and the metallic rib 3 are covered by a varnish layer 5 protecting

them against atmospheric influences. Upon that part of the varnish layer 5 which covers the ring-shaped reinforcing rib 3 a further correspondingly shaped metallic layer 6 is sprayed in such manner that a part of the sprayed-up metal particles is forced through the varnish layer covering the rib 3 and thus brings the layer 6 into good conductive contact with the rib 3. This may be easily accomplished as the speed of the sprayed metal particles with which they meet the varnish layer may be easily regulated by varying the strength of the gaseous stream carrying the particles and be increasing or decreasing the distance of the spraying device from the cell in such a manner that they do not penetrate the varnish but merely cover it or in such a manner that they penetrate the varnish. As soon as the varnish layer is penetrated by the metal particles, a conductive contact is made between the rib 3 and that portion of the metal particles which remains in the varnish, for the metal particles force their way through the varnish in the manner innumerable bullets would and thereby build up an efficient conductive contact through the varnish layer. The metallic layer 6 can now be used as one of the terminals of the cell while the covering layer 4 is hermetically sealed by the varnish layer 5.

What I claim is:

30 1. The method of producing photoelectric cells

of the layer type which consists in providing the translucent conductive covering layer with reinforcing ribs of conducting material in contact with said covering layer, covering the said covering layer and reinforcing ribs with a thin translucent layer of varnish, and spraying upon those parts of said varnish layer which cover the said reinforcing ribs, conducting material under such conditions that the varnish layer is pierced by the sprayed material. 10

2. Photoelectric cell of the layer type comprising a base plate, a layer of light sensitive material upon said base plate, a translucent conducting covering layer upon and in intimate contact with the surface of said light-sensitive layer, reinforcing ribs of conducting material in contact with said covering layer, a layer of varnish upon said covering layer and said reinforcing ribs, and a further layer of conducting material upon those parts of the varnish layer which cover the said reinforcing ribs, said further layer of conducting material being in conductive connection with the said reinforcing ribs. 15 20

3. Photoelectric cell according to claim 2, wherein said further layer of conducting material partly penetrates through the said varnish layer and thus is in conductive connection with the said reinforcing ribs. 25
